[57] CLAIM

The ornamental design for a lighting device for plants, as shown.

DESCRIPTION

FIG. 1 is a perspective view of the lighting device for plants showing our new design in the upright position;

FIG. 2 is a front elevational view, the back elevational view being identical thereto;

FIG. 3 is a top plan view of the device;

FIG. 4 is a right side elevational view of the device; and

FIG. 5 is a left side elevational view of the device; and, FIG. 6 is a perspective view of the lighting device in the lowered position.

The bottom view is omitted since it is plain and unornamented.

The broken lines are shown for illustrative purposes only and form no part of the claimed design.
